UNITED STATES PATENT OFFICE.

CLAUDIO BUSCHETTI, OF MILAN, ITALY.

ELECTRIC INSULATOR.

1,205,971.

Specification of Letters Patent. Patented Nov. 28, 1916.

Application filed April 10, 1915. Serial No. 20,563.

To all whom it may concern:

Be it known that I, CLAUDIO BUSCHETTI, a subject of the King of Italy, residing at 115 S. Cristoforo, Milan, in the Kingdom of 5 Italy, have invented certain new and useful Improvements in Electric Insulators, of which the following is a specification.

In order to connect insulators with their supporting rods, metallic members such as 10 screw-threaded sleeves, caps or pins were hitherto used and secured to the insulator by screwing or more often by cement, or putty. In any case these members were manufactured independently and separately 15 from the insulator to which they were secured by any of the aforesaid means. When using a screwed connection, there is the difficulty of making the metallic screw-thread fit exactly the porcelain. Putty and cement 20 give rise to two drawbacks; in the first place they are liable to be broken up by shocks and the constant oscillation of the electric lines, and secondly they completely and rigidly fill the cavity of the insulator within 25 which the metallic portion is fixed so that when the temperature of the insulator becomes higher than it was at the time the cementing took place it is liable to be fractured owing to the pressure exerted from 30 within by the cement due to the expansion of the heated metal. This is caused by the difference in the thermal co-efficients of expansion of these two materials and the insulating material. In addition thereto, 35 chemical reactions take place between the putty or cement or metal thereby producing an increase in the volume and thus cause the bursting of the insulator without the assistance of heat. The present invention eliminates 40 these drawbacks as the metal which is to constitute the connecting member of the insulator, is fixed directly on the surface which is to receive the same, without the use of cement, putty or any mechanical elements but merely by means of a galvanoplastic process. It is obvious that the galvanic 45 deposit may connect the insulator with other metallic parts which have not been obtained electrolytically.

50 In the accompanying drawings:—Figure 1 illustrates, in section and elevation, one

form of the connection effected in accordance with the invention. Fig. 2 illustrates a modification in section.

a is the metallic sleeve formed with a 55 screw-thread, which has been provided in the insulator *d* directly by electrolytic means; into this sleeve the pin or support of the insulator may be introduced by screwing, irrespective of the fact whether the screw-thread has been obtained during the electro-galvanic deposition or whether it has been formed subsequently. The screwed connection may be replaced by any other connection, for example mechanical, electrical, or 60 by solder. For instance, Fig. 2 illustrates another form which may be given to the electro-galvanic connection. *d* is the insulator and *b* is a metallic sleeve formed with a screw-thread screwed on to the galvanic 65 deposit *a* which is partly or wholly covered thereby. The said sleeve may be connected with any pin or support having an internal or external screw-thread, or by any other mechanical means. The method above described 70 may also be used for connecting insulators with one another.

What I claim and desire to secure by Letters Patent of the United States is:—

1. In combination, an electric insulator 80 body, a recessed portion thereon, a metallic sleeve electrolytically deposited upon the inner portion of the recess and projecting freely within said recessed portion, means upon the projecting portion for attaching 85 another sleeve thereto and a sleeve thereon adapted to be secured to a supporting member, substantially as set forth.

2. In combination, an electric insulator 90 body, a recessed portion thereon, a metallic sleeve electrolytically deposited upon the inner portion of the recess and projecting freely within said recessed portion, a thread upon the projecting portion and a sleeve thereon adapted to be secured to a support- 95 ing member, substantially as set forth.

In testimony whereof I affix my signature in presence of two witnesses.

CLAUDIO BUSCHETTI.

Witnesses:

AUGUSTA RICHANY,
LYLE ROBB.
